UNITED STATES PATENT OFFICE

113,952

DESIGN FOR A SUIT

Samuel Zimmerman, New York, N. Y.

Application February 7, 1939, Serial No. 82,829

Term of patent 3½ years

To all whom it may concern:

Be it known that I, Samuel Zimmerman, a citizen of the United States of America, residing in New York city, in the Borough of Manhattan, county and State of New York, have invented a new, original, and ornamental Design for a Suit, of which the following is a specification, reference being had to the accompanying drawing, forming part thereof, wherein—

I claim:

The ornamental design for a suit, substantially as shown.

SAMUEL ZIMMERMAN.
